M. C. Dart INVENTOR

UNITED STATES PATENT OFFICE.

MELVIN C. DART, OF NEW YORK, N. Y.

BURGLAR ALARM.

Application filed February 7, 1921. Serial No. 442,959.

To all whom it may concern:

Be it known that I, MELVIN C. DART, a citizen of the United States, and a resident of New York city, in the county and State 5 of New York, have invented certain new and useful Improvements in a Burglar Alarm, of which the following is a full, clear, and exact description.

Among the principal objects which the 10 present invention has in view are: to provide an alarm which is not subject to being tampered with by a person operating from the outside of the door; to provide an alarm which operates continuously after the door 15 has been moved inward from its initial locked position; to provide a dead lock and alarm attachment thereto to various working conditions; to provide an alarm which is easily transported and universally adjusted to doors and closure members of usual construction; and to simplify and cheapen 20 the construction of the alarm.

Drawings.

25 Figure 1 is a horizontal section of a door and frame therefor showing a burglar alarm mounted thereon as in service relation thereto.

Figure 2 is a front view of the same showing fragments of the door and frame and the inner end of the alarm.

Figure 3 is a detailed view on enlarged scale showing an alarm constructed and arranged in accordance with the present invention and disposed as in service.

Figure 4 is a side view of the same.

Figure 5 is a detailed view on enlarged scale and in section, the section being taken as on the line 5—5 in Figure 4.

40 Figure 6 is a modified form of the invention on a diminished scale for permanent installation on the frame of a door.

Description.

45 As seen in the drawings the preferred form of the invention is adapted for temporary installation in active position. To this end the bar 11 is provided at its forward end with an offset hook 12 adapted for 50 insertion within the bolt socket 13 with which the door frame is usually provided. At the inner end as best seen in Fig. 4 of the drawings, the bar 11 is bifurcated by forming the open-ended slots 14 therein.

55 The slot 14 forms a guide and runway for a screw bolt 15 fixedly attached to a plate 16

which slides on the bar 11. The plate 16 is further provided with overturned clips 17 which and as will be seen in Fig. 4, partially surround the edges of the bar 11.

The plate 16 together with the clips 17 and the bolt 15 form a stop for a slidable locking member provided with a foot 18 to be engaged by the door 19 when the same is moved to open position. The locking member has overturned edges 20 which guide said locking member in its movement lengthwise of the bar 11. The foot 18 is reinforced and supported by a brace 21 formed by an extension of the metal from which the said foot is formed, the free end of the brace resting in the angle formed by the bracket 22.

It will be seen that whenever the plate 16 is rigidly attached to the bar 11, the end thereof with the clips 17 limit the movement of the locking member. In practice the plate 16 and locking member are drawn back so that the hook 12 may be inserted in the socket 13 prior to closing the door 19. The door 19 is then closed, forcing the hook 12 into the socket 13 to hold the same therein. The locking member is then moved forward until the foot 18 presses slightly on the inner side of the door 19. The plate 16 is 85 moved forward toward the lock member and if it is desired to form a dead-lock for the door, the plate 16 is moved until it engages the lock member.

A variety of means may be used for holding the plate 16 stationary on the bar 11. That shown in the drawings is to provide a series of forwardly inclined teeth 23 with which corresponding teeth formed in a washer 24 fit. The washer 24 is slidably 95 mounted on the bolt 15 and is pressed into engagement with the bar 11 and the teeth 23 thereof by the wing nut 25, the threads of which engage the threads on the bolt 15.

The alarm bell 26 is made in any suitable 100 manner. That shown in the drawings is a bell having a spring operated striking mechanism which is released by a plunger 27. The bell is mounted by means of a bracket 28 on the plate 16, to which it is 105 permanently secured. The disposition of the bell 26 on the plate 16 is such that the end of the plunger 27 protrudes slightly ahead of the end of the plate 16 and the clips 17 thereof. The plunger 27 is disposed in the path of the bracket 22 and engages the same to be moved thereby to

release the spring actuated mechanism for the bell 26 prior to the body of the locking member engaging the plate 16 or the clips 17. Thus, in practice, when the alarm bell 5 is employed before the dead lock of the bar 11, plate 16 and locking member thereof becomes effective, the audible alarm is inaugurated and continued.

In Fig. 6 of the drawings a modified 10 form of the invention is shown. The modification consists in providing a hinge 29 connecting sections of the bar 11. The forward section is held permanently on the frame of the door by means of screws 30 15 or other suitable fastening devices. When permitted, the inner end of the bar carrying the bell 26 and locking member may be swung out of the path of the door 19, the alarm being then inactively disposed. 20 When, however, it is desired to place the alarm in active position, the swinging portion of the bar 11 is moved to the position shown in Fig. 6 of the drawings, and a hinged brace 31 having a friction foot 32 25 made of rubber or other suitable material is swung on its hinge 33 by which it is connected to the clips 17 until the foot 32 engages the frame of the door. It is evident that when the door 19 now presses 30 against the foot 18 of the locking member, the bar 11 is prevented from swinging on the hinge 29 by the brace 31 and the foot 32 thereof.

It is evident that alarm mechanism 35 constructed and arranged in accordance with

the present arrangement may be transported by salesmen or other persons traveling, to be temporarily installed in active position on a closed door so that a person in a hotel or other temporary habitation may 40 close the door and adjust the alarm thereto in such a manner as to avoid the possibility of opening the door without first arousing him.

Claim.

45

A burglar alarm comprising a continuously operable audible alarm normally restrained from operating: a supporting bar for said alarm, said bar having at approximately one extremity, an offset hook for engaging a socket in a standing structure, and a series of detent members disposed between the extremities of said bar; means for mounting said alarm on said bar, said means embodying a bracket for said alarm slidably mounted on said bar, and an adjustable locking member mounted on said bracket for engaging said detent members, and a manually operated screw member for 60 clamping said bracket on said bar; and a bracket slidably mounted on said bar for releasing said alarm when said bracket is moved toward said alarm, said bracket being arrested in its movement by the supporting bracket of said alarm for preventing the entrance opening of a door or window member operatively engaged with said alarm.

MELVIN C. DART.
